UNITED STATES PATENT OFFICE

2,434,011

VOLTAGE-LIMITING ARC INTERRUPTER

Ralph R. Pittman, Park Hill, Ark.

Application January 29, 1945, Serial No. 575,081

1 Claim. (Cl. 175—30)

1

This invention relates to excess-voltage protective devices for use with alternating current systems, for the purpose of preventing an excessive superimposed voltage rise on a conductor or connected apparatus, such as might be caused by lightning.

Among the objects of the invention may be noted: (a) the provision in an arc extinguishing device embodying spaced conducting electrodes within an expulsion tube and a filler between the electrodes, of means for rigidly supporting the filler in lateral abutting relation with the tube; (b) the provision of means for so distorting the electrostatic field prior to sparkover between the electrodes to cause sparkover to occur adjacent to the line of abutment of the filler with the tube; (c) the provision of a discharge path providing a low initial sparkover voltage along with an arc path which may be taken by an arc following sparkover which varies in cross-sectional area, the length and area of the arc path being so related as to effect arc extinguishment; and (d) the provision of a novel electrostatic flux control construction for reducing the sparkover voltage between the electrodes and along the abutment line to a quantity less than that of any other path between the electrodes.

With the above and other objects in view which will appear from the description, my invention resides in the novel arrangement for supporting the filler, and in the electrostatic field control arrangement for effecting sparkover along a predetermined desired path, together with the combination of elements for accomplishing arc extinguishment which are so disposed as to assist in effecting the desired flux control, thus making possible the attainment of the desired results with a minimum of parts, and greatly simplifying the structure.

In the drawing: Fig. 1 is an elevational view of an embodiment of the invention, shown partly in section; Fig. 2 illustrates in elevation the external appearance of the structure; and Figs. 3 and 4 are fragmentary sections taken respectively along the lines 3—3 and 4—4 of Fig. 1. Similar reference characters indicate like elements in the several figures of the drawing.

Referring detail to the embodiment of the invention illustrated, a tube 17, of insulating material, e. g. hard fiber, is internally threaded at its upper end, and threadedly engaged by the downwardly extending bushing of conducting material 15. Near and somewhat above the lower end of the tube 17 a terminal bolt 22, of con-

2

ducting material, having a diameter less than that of the bore of the tube extends transversely therethrough and outwardly externally of the tube. A bracket member 25, of some suitable metal (partially shown) is clamped between the nuts 24 and 26, the latter members threadedly engaging the outwardly extending portion of the terminal bolt 22, and thus providing a mounting and lower terminal for the device.

10 A cylindrical filler 18, of insulating material, e. g. hard fiber, having a diameter less than that of the internal diameter of the tube 17, is beveled at its respective ends, and the conducting upper and lower electrodes 19 and 20 respectively are 15 fitted on the filler in conformity with the bevel of the respective beveled ends, the upwardly and downwardly extending arms of the electrodes being longitudinally spaced on the filler. The lower sloped or beveled surface of the electrode 20 rests on the transversely extending terminal bolt 22, and the adjustable metal terminal screw 12 extends downwardly through internal threads of the bushing 15 to engagement with the oppositely beveled upper surface of the 20 upper electrode 19, rigidly wedging the filler 18 in lateral abutting relationship with the inner surface of the tube 17. The upper end of the adjustable terminal screw 12 is shown spaced from a conductor 10 by the spark gap indicated 25 by the numeral 11.

To provide housing, a sleeve 23 extends upwardly along the outer surface of a lower-end portion of the tube 17, being held in place by the passage of the terminal bolt 22 therethrough. At 30 its upper end, the sleeve 23 is provided with an outwardly extending flange for supporting the housing 16, the latter extending upwardly above the upper end of the tube 17. The upper end of the housing 16 is closed by the cover 14, which 35 is clamped between the upper end of the bushing 15, and the lock nut 13 of the terminal screw 12. The housing 16 is preferably formed from weather-resistant insulating material, such as 40 glass or porcelain.

45 A sleeve of conducting material 21 is fitted tightly around the outside of the tube 17 between the terminal members of the device. For reasons shortly to appear, the sleeve 21 is preferably beveled so that its greatest lengthwise dimension 50 along the tube is nearest to the line of abutment of the filler 18 with the tube 17, and its smallest lengthwise dimension along the tube is along a line diametrically opposite the abutment line.

While such a construction is not essential to 55 the successful operation of the invention, it is

convenient for the purpose of describing the operation of the invention to assume that the longitudinal distance between the electrodes 19 and 20 along the line of abutment, or from the portion 27 of the upper electrode 19 to the portion 29 of the lower electrode 20, is equal to the longitudinal distance along a line diametrically opposite the line of abutment, or from the portion 28 of the upper electrode 19 to the portion 30 of the lower electrode 20. It is essential that the conducting members are so coordinated with the insulating members that the weakest electrical path between the terminal members of the device is longitudinally along the filler between the electrodes 19 and 20.

When an increasing voltage is applied between the electrodes 19 and 20, the electrostatic flux prior to gap sparkover from the electrode 19 to the electrode 20 follows the path of lowest reluctance, and is thereby concentrated along a line through the wall of the tube 17 between the portion 27 of the upper electrode 19 and the uppermost portion 31 of the sleeve 21, and along a line through the wall of the tube 17 between the lowermost portion 32 of the sleeve 21 and the portion 29 of the electrode 20. Relatively, only an insignificant amount of flux passes from the portion 28 of the electrode 19 to the portion 33 of the sleeve 21, or from the portion 34 of the sleeve 21 to the portion 30 of the electrode 20, because of the relatively wide separation of these conducting elements.

As a result of the above-mentioned flux concentration, streamers are originated at the points of maximum flux density and extend respectively downwardly from the portion 27 of the electrode 19 and upwardly from the portion 29 of the lower electrode 20. These streamers in effect reduce the length and therefore the sparkover voltage of the gap to an amount less than that which would be required in their absence. For this reason, and despite the fact that the distance from the portion 27 to the portion 29 may be equal to the distance from the portion 28 to the portion 30, sparkover occurs along the abutment line rather than along any other path between the electrodes.

Any ensuing alternating current arc follows the sparkover path, thus setting up the desired condition for alternating current arc extinguishment. Because once the alternating current arc is established along the path of greatest restriction, it immediately seeks the path of least restriction. In so doing, it moves peripherally around the filler, and is extinguished through contact with the relatively cold surfaces passed over and the attendant cooling gases evolved therefrom. In applying the device, it is necessary that the distance between the electrodes be sufficient that, under the conditions of operation, the normal circuit voltage will be incapable of sustaining an arc along the path of least restriction following its movement from that of greatest restriction. This is a consideration related to both length and relative diameters of filler and tube, and as one example, a tube having a diameter of $\frac{3}{4}$ ", a filler having a diameter of $\frac{11}{16}$ ", and an electrode spacing of 2", has been

found to be a satisfactory combination for application to alternating current circuits up to voltages of 9 kv., R. M. S. A construction for causing the herein mentioned arc movement around the filler has been heretofore described in more detail in Patent No. 2,164,720, dated July 4, 1939, and issued to Ralph R. Pittman.

Preferably the sleeve 21 is formed of tempered steel or other material having high strength, so that it may also function as mechanical reinforcement for the wall of the tube. The maximum impact occurs along the abutment line, and it is along this line that the maximum length of sleeve is disposed.

15 The invention herein disclosed is similar in certain respects to that shown in my copending application Serial No. 573,572, which, however, does not embody the means herein illustrated and described for controlling sparkover.

20 It is intended that the specific illustration and description of the invention herein presented will be regarded as illustrative rather than limiting.

I claim as my invention:

25 A voltage-limiting arc interrupter comprising a hollow tube of insulating material having at least one end open, a cylindrical filler of insulating material extending longitudinally therein and partially filling said tube, means holding said filler in lateral abutting relation with said tube, 30 normally insulated conducting electrodes spaced apart at the respective ends of said filler and arranged to provide a preferential sparkover path between them along said filler and within said tube, the sparkover path along the line of abutment being substantially equal to that along the parallel line diametrically spaced from said line of abutment, and flux control means for concentrating prior to sparkover the flux between 35 said electrodes adjacent to the line of abutment 40 of said filler with said tube, said flux control means comprising a sleeve of conducting material fitted tightly around the outside of said tube in insulated relationship to at least one of said electrodes, said sleeve being provided with beveled ends and so mounted on said tube that the longest dimension of said sleeve is nearer to said line of abutment than to any other portion of said filler.
